UNITED STATES PATENT OFFICE.

PAUL SWITZENY, OF VIENNA, AUSTRIA.

MACHINE FOR FIXING CLASPS.

Application filed May 26, 1927, Serial No. 194,435, and in Austria June 1, 1926.

This invention relates to improvements in machines for fixing clasps on packets or packages, such as for instance a number of sheets or the like which are to be fixed together, in which U-shaped wire or sheet metal clasps are fixed to the articles, which are to be bound together, by a blow applied to the head-piece of a driver, and whereby with the same machine also cardboard or like rolls and boxes can be stapled or fixed together. In the case of fastening pliers it has been proposed already to dispose the fixing head at the side of the plane of the pliers-limbs and to arrange the clasps-guide parallel with respect to the pivot of the pliers. However such an arrangement does not satisfy the demands, because the limbs of the U-shaped clasps which have to be bent up or down are located at a different distance from the axis of rotation or pivot and therefore, on pressing the limbs against the sheets to be fixed together, the limb which is more remote from the said axis of rotation or pivot is not compressed to the same extent as the limb which is located nearer to the said axis or pivot, this drawback increasing with the thickness of the articles to be fastened together. This drawback is not greatly felt in the case of fastening pliers, because already in consequence of the smaller compression, effected solely by closing the limbs of the pliers, only a small number of sheets can be fastened together. In the event of a large number of paper-sheets it may be the case, that the limb of the clasp located at the outside does not sufficiently extend out at the backside of the paper parcels or package to be fastened together, so that the end of it cannot be turned down onto the paper. According to the present invention this drawback is removed, in that the axis of rotation or pivot of the hinged plates of the machine is disposed vertically with respect to clasps-guide, whereby the fixing head is located laterally. Both clasp-limbs are now disposed the same distance away from the axis of rotation and on striking the fixing head simultaneously contact with the bed-die and are compressed with the same force on the sheets to be fastened together, so that both clasp-limbs are securely fixed even in the case of a machine with displaced fixing head.

In order to render possible the fixing of rolls sleeves or boxes, the bed-plate, which is widened in consequence of the lateral dispo-

sition of the fixing head, is provided with a recess extending parallel with respect to the fixing plane, so that two arms are formed on the bed-plate, whereby the arm most remote from the axis of rotation carries the die co-operating with the head-die. Rolled sleeves or the like of a pliable strip can be pushed over this small arm and can be fastened together, whereby the middle or connecting portion of the U-shaped clasps lies in the direction of the axis of the roll.

One mode of carrying out the present invention is illustrated by way of example on the accompanying sheet of drawing in which:

Figs. 1 and 2 show the machine for fixing clasps in plan view and side view respectively.

A top-plate 4, carrying a fixing head 3 and a clasps-magazine 7, is hinged to the rectangular bed-plate 1 by a hinge 5, which is arranged in the corner of the bed-plate and the axis of rotation of which extends parallel to the longitudinal side of the bed-plate. The fixing head 3 is constructed in known manner and is disposed in that corner of the top-plate 4, which lies diagonally opposite the corner of the hinge 5, while the clasps-magazine 7 is disposed vertically and laterally to the shaft of the hinge 5. The U-shaped clasps, which are automatically fed to the top-die by a spring 8, are located vertically with respect to the longitudinal direction of the magazine 7. At any angular position of the top-plate 4, the limbs of the clasps are the same distance away from the elongated imaginary axis of the hinge, and therefore simultaneously meet the bottom-die 9 and are pressed onto the backside of the articles to be fastened together with a like force when striking the knob 6 of the head-die.

The forward end of the bed-plate 1 is provided with a recess, whereby two arms are formed, which extend parallel with respect to the fixing line. The end of the arm 2 thus formed lies underneath the bottom-die 9 and the top-die, located in the fixing head 3. The other arm of the bed-plate serves for maintaining the stability of the machine when striking the knob 6 of the top-die. The arm 2 can be of any convenient small width, in order to push rolls or sleeves of a small diameter over the fixing or fastening place and unite the overlapping edges of the rolled paper-strips by clasps. Thereby the backs of the clasps are disposed in the direction of the axis of the cylindric tube or sleeve.

I claim:—

1. A machine for fixing U-shaped clasps on a package, comprising in combination a bed-plate having a recess therein providing 5 two spaced arms, a top-plate hinged to the bed-plate at one corner thereof, a clasps-guide arranged on the top-plate and disposed at a right angle with respect to the axis of rotation of the said top-plate, a head provided 10 with a driver secured to the top-plate and disposed laterally with respect to the axis of rotation of the said top-plate above that arm of the bed-plate which is most remote from the said axis of rotation, and a die secured 15 to the bed-plate arm last mentioned.

2. A machine for fixing U-shaped clasps on a package, comprising in combination a bed-plate, a top-plate hinged to the latter at one corner thereof, a clasps-guide arranged on the top-plate and disposed at a right angle 20 with respect to the axis of rotation of the said top-plate, and a head provided with a driver secured to the top-plate and disposed laterally with respect to the axis of rotation 25 of the said top-plate above that corner of the bed-plate which is most remote from the said axis of rotation.

In testimony whereof I affix my signature.

PAUL SWITZENY.
